UNITED STATES PATENT OFFICE.

EUGENE T. KIEFFER, OF PHILADELPHIA, PENNSYLVANIA, ASSIGNOR TO VICTOR
TALKING MACHINE COMPANY, A CORPORATION OF NEW JERSEY.

DESIGN FOR A CABINET FOR TALKING-MACHINES.

49,215.

Specification for Design.

Patented June 20, 1916.

Application filed February 11, 1915. Serial No. 7,603. Term of patent 14 years.

To all whom it may concern:

Be it known that I, EUGENE T. KIEFFER, a citizen of the United States, residing at Philadelphia, in the county of Philadelphia and State of Pennsylvania, have invented a new, original, and ornamental Design for Cabinets for Talking-Machines, of which the following is a specification, reference being had to the accompanying drawing, forming a part thereof.

The figure is a perspective view of a cabinet for a talking machine showing my new design.

I claim:

The ornamental design for a cabinet for a talking machine, as shown.

EUGENE T. KIEFFER.

Witnesses:

MARGUERITTE McFALLS,

CHARLES F. WILLARD.
